COMBINATION HANDLE AND SUPPORT LEG
FOR IRONER CABINETSCharles M. Hall, Trumbull, Conn., assignor to
General Electric Company, a corporation of
New York

Application August 1, 1951, Serial No. 239,732

2 Claims. (Cl. 312—241)

1

The present invention relates to covers for ironer cabinets and more specifically to combination handles and supporting legs therefor.

Many ironer tables are equipped with box covers for enclosing the ironer when not in use. These covers are usually pivotally mounted on the tables so that they can be readily and easily moved out of the way at the beginning of an ironing operation, and each provided with one or more legs so that it can be supported on the floor at a height convenient for use by the operator as an auxiliary table surface. Such legs must be latched in their supporting positions and means should be provided for readily releasing them so that they can be folded against their respective covers when the latter are closed on the ironer table. My invention is concerned with latching and release means for such supporting members, and with means for making them more readily available for use as cover handles.

The object of my invention is to provide an improved support leg construction for the cover for an ironer table.

Another object of my invention is to provide an improved latch and release means for the support leg.

A further object of my invention is to provide means by which the support leg can be readily moved into position for use as a handle for removing the cover from the ironer table.

In carrying out my invention, I affix to the front wall of an ironer cover a decorative trim member which serves as a base portion for my combination handle and support leg structure. This structure further includes a bar or rod which is pivotally mounted intermediate its ends on a pintle supported in the trim or base member. Resilient means are employed to form a latch cooperating with the short end of the bar to lock it in its open or extended position in which it serves as a support leg. Manually operable means, preferably in the form of a push-button, are provided for releasing the latch to permit return of the bar to its closed position in which it is folded against the base. The latch forming resilient means may be arranged to bias the bar toward this closed position in which case the pushbutton can be used to remove the bias to permit the bar to be returned more readily to its extended position. Moreover, the pushbutton can be so constructed and positioned that it will engage a portion of the short end of the bar and, in addition to relieving the spring bias, will move the bar toward its open position so that it can be readily grasped, pulled to its fully open

position, and used as a handle to remove the cover from the ironer table.

My invention will be better understood from the following description taken in connection with the accompanying drawing, and its scope will be pointed out in the appended claims.

In the drawing, Fig. 1 is a perspective view of an ironer table embodying my invention, with its cover in the closed position; Fig. 2 is a perspective view of the ironer table showing the cover in its final open position, with the support leg extended; Fig. 3 is a fragmentary front view of the cover for the ironer table, showing the combination handle and support leg with the bar in its closed position; Fig. 4 is a section taken along the lines 4—4 of Fig. 3; Fig. 5 is a section taken along the lines 5—5 of Fig. 3 but showing the bar, not in section, in full lines in its fully opened or extended position and in dotted lines in its partly open position.

Referring to the Figs. 1 and 2, there is shown an ironer table 1 having a top 2 provided with downwardly extending flanges 3 at the side and end. In the corners of the table top are secured supporting legs 4. This table provides a support for an ironer which may be of the construction shown in the copending application of Robert E. Sheahan, Serial No. 108,837 filed August 5, 1949, and assigned to the General Electric Company, assignee of the present application. As shown in Fig. 2, this ironer comprises the usual heated shoe 5 which may be moved into and out of register with a padded buck 6 by suitable automatic mechanism such as the hydraulic motor system shown in the aforementioned Sheahan application. During the periods when the ironer is not in use, it is enclosed by a box cover 7 having a front wall 8, end walls 9, a top wall 10 providing a table top, and a rear wall 11.

In the rear left hand corner of the table top 2 are provided hinging means, not shown, for securing of the cover 7 to the table 1 and by which the cover 7 may be swung first to a vertical position alongside the table and then to the horizontal position of Fig. 2. The hinging means may be of any suitable known construction such as any one of the three types shown in the patent to George W. Wardwell, Jr., 2,198,467, for a Table for Ironers and the Like, assigned to the General Electric Company, assignee of the present application.

When the cover 7 is supported in the position shown in Fig. 2, the front cover 8 and the rear cover 11 provide a shelf and a work surface respectively on which the freshly ironed clothes or

other articles may conveniently be placed. In order to support the cover at the desired height, it is common practice to provide a support leg that is pivotally mounted relative to the front cover panel so that it can be opened to an extended position when needed as a leg and folded to a closed position adjacent the cover when not in use. It is desirable that it be so constructed that it can be used as a handle by which the cover can be moved from its closed to its final open position and from its open position back to its closed position. Moreover, the rather plain front portion of the ironer table and cover can be advantageously broken by the provision of an attractive trim member on the cover, thereby making the appearance more pleasing.

In designing a handle and leg structure incorporating all of these desirable features, I have combined the leg and handle function in a single bar 12 and have provided a decorative trim member 13 secured to the cover wall 8 and serving as the base on which the bar 12 is mounted. Pivotally mounted in the trim member or base 13 is a pivot pin or pintle 14 passing through the bar 12 intermediate its ends but near the right hand end thereof, as viewed in Fig. 3. The bar 12 fits securely on the pintle 14 but the bar and pintle can be pivotally moved about the pintle mounting in the base 13 from a folded or closed position adjacent the cover and trim member to an open or extended position as shown in Figs. 2 and 5.

The base 13 may be secured to the wall 8 by a plurality of screws 15. In the wall 8 is provided a slotted opening 16 in the vicinity of the pintle 14, in alignment with an equivalent opening in the base member, as seen in Fig. 5, and of sufficient size to permit the short end of the rod 12, extending to the right of the pintle as seen in Fig. 4, to pass through it upon movement of the bar to its extended position.

In order to insure that the bar 12 will remain in its extended position when used as a support leg, I provide latch means as best shown in Figs. 4 and 5. On the opposite side of the wall 8 from the base 13, I affix to the base, by means of several of the screws 15, a leaf spring 17. From a fixed end 18, the spring 17 extends adjacent the wall 8 and is provided with a reverse Z-shaped latch portion having walls 19, 20 and 21. The reverse Z-shaped latch portion is positioned directly adjacent the opening 16. The short end of the bar 12 extending to the right of the pintle 14 is provided with a notched upper corner 22 as viewed in Figs. 4 and 5. When the bar 12 is manually lifted to its open or extended position, the notched corner fits snugly in the latch portion of the spring 17 with the walls of the notched corner in contiguous relation with the walls 19, 20 and 21. In this manner, as well as by abutment of the bar end against a portion of the base 13, the bar 12 is held against movement beyond its open position or toward its folded position. Of course, if an unusually large force were applied against the bar 12, the vertical wall portion of the notch 22, as seen in Fig. 5, would cam the spring 17 out of position and release the latch. Consequently, this construction provides a latch which is effective to lock the rod or bar 12 into position securely enough to support the cover 7 under most conditions but which will release to prevent damage to the cabinet cover if the bar is struck with an unusually large force.

In order to quickly and easily release the latch

to permit movement of the bar from its open to its closed position, I provide means for moving the latch portion of the spring 17 out of engagement with the notched end 22 of the bar. The spring 17 is provided with an extended portion 23 at its free end. A pin 24 is journaled in the base 13 for slidable movement in a direction parallel to the bar when the latter is in its open position. It is provided with a shoulder 25 at its lower end as seen in Fig. 5, which limits its axial movement in the upward direction. On its opposite end is secured a pushbutton member 26 by which it can be pushed downwardly, as viewed in Fig. 5, or inwardly as viewed in Figs. 1 and 3. In order to return the pushbutton member 26 to its operating position after each operation, I have provided a coil spring 27, one end of which bears against the base 13 and the other end of which bears against the underside of the pushbutton. The pin 24 passes through the base and through the wall opening to engage the extension 23 of the leaf spring. Consequently, when the pushbutton member 26 is depressed, the pin 24 deflects the extended member 23, thereby moving the latch portion of the spring 17 out of engagement with the notched end 22 of the bar. While continuing to depress the button 26, the operator need only lightly press the bar 12 to move it from its open to its closed position.

Another advantageous feature of my handle and leg construction is the provision of means biasing the bar toward its closed position so that it will remain securely closed until needed for use as a handle or support. A simple means of doing this is shown in Fig. 4 in which the leaf spring 17 is provided with an inverted V-shaped portion 28 extending through the opening 16 in the cover wall, where it bears against a rounded lower edge 29 as seen in Fig. 4, of the short end of the bar 12. The long end of the bar 12 is thereby biased toward its closed position by the force of the spring 17, though this bias can be easily overcome if the operator grasps the bar and pulls it. The biasing force of spring 17 is released if the operator first depresses the button 26, since the pin 24 then moves the spring away from the bar. Release of the bias can be accompanied with partial opening of the bar. To accomplish this, I form on the pushbutton 26 a cam portion 30 engageable with a shoulder of the notched end 22 of the bar, as shown in Fig. 4. In the construction as shown when the button 26 is depressed, it simultaneously moves the spring 17 to relieve the biasing force and depresses the short end of the bar. Since the distance between the notched end 22 from the bar and the pintle 14 is very small compared to the distance from the pintle to the opposite end of the bar, the small movement imparted by the button 26 causes a greatly magnified movement of the long end of the bar so that it will assume approximately the position shown in dotted lines in Fig. 5. It will then be very convenient for the operator to grasp the bar and move it to its fully extended position where it can be used either as a handle or a support leg as previously explained. In case an operator does not desire to perform this function in two steps, I have provided a recess portion 31 in the bar 12 to serve as a finger grip so that it will be a simple matter to pull the bar open, overcoming the bias of the spring 17, without using the pushbutton.

The cam portion 30 of the button 26 additionally may serve as an auxiliary stop to prevent opening the bar 12 beyond its vertical posi-

tion relative to the base, as seen in Fig. 5. The latch portion of the spring 17 cooperates with the notched end 22 of the bar to prevent any substantial movement beyond the vertical position but construction of the cam 30 so as to provide an additional stop is obviously advantageous. Also, as previously explained, the slotted opening 16 in the wall 8 permits the short end of the bar to extend through the equivalent base opening whereupon it abuts a portion of the base 13 and is thereby prevented from movement beyond its vertical position.

While I have shown a particular embodiment of my invention, it will be understood, of course, that I do not wish to be limited thereto, since many modifications may be made; and I therefore contemplate by the appended claims to cover any such modifications as fall within the true spirit and scope of my invention.

What I claim as new and desire to secure by Letters Patent of the United States is:

1. A combination handle and support leg for a pivotally mounted ironer cover, comprising: a base member secured to said cover, a bar pivotally mounted in said base member, a leaf spring secured to said base member and shape to engage one end of said bar eccentrically of its pivotal axis with a force directed to bias said bar into closed position, and manually operable means engaging with said leaf spring and said bar end eccentrically of its pivotal axis and movable in a direction opposed to the direction of said leaf spring force to move said bar toward its open position.

2. A combination handle and support leg for a pivotally mounted ironer cover or the like com-

prising a base member secured to said cover, a bar pivotally mounted in said base member intermediate its ends, said bar having a relatively short portion on one side of its pivotal axis and a relatively long portion on the opposite side of said axis, a leaf spring fixed at one end to said base member with its opposite end movable in a direction substantially perpendicular to said pivotal axis and biased toward and into engagement with the short portion of said bar, a shouldered portion adjacent the end of said spring engageable with the end of the short portion of said bar to maintain the long portion thereof in an extended position perpendicular to said cover, a projection on said spring engageable with the short portion of said bar as it is moved toward a position parallel to said cover thereby to bias said bar into a retracted position parallel to said cover, and push-button means having a spring actuator and a bar actuator movable conjointly, said spring actuator forcing the movable end of said spring away from said bar while said bar actuator engages the short portion of said bar to move the bar toward said extended position.

CHARLES M. HALL.
